UNITED STATES PATENT OFFICE.

WALTER H. COTTON, OF CHICAGO, ILLINOIS.

ELECTRIC IGNITER FOR GAS-ENGINES.

SPECIFICATION forming part of Letters Patent No. 634,430, dated October 3, 1899.

Application filed October 24, 1898. Serial No. 694,470. (No model.)

To all whom it may concern:

Be it known that I, WALTER H. COTTON, a citizen of the United States, residing at Chicago, in the county of Cook and State of Illinois, have invented a new and useful Improvement in Electric Igniters for Gas-Engines, of which the following is a specification.

The objects of this device are to secure a maximum of efficiency with a minimum out-
10 put of mechanical apparatus and at the same time eliminate the noise and vibration usually accompanying apparatus of this character; also, in view of its simplicity reducing cost of construction without impairing its effi-
15 ciency.

The apparatus is illustrated in the accompanying drawings, in which—

Figure 1 is a plan view showing the electromagnetic operator. Fig. 2 is a view of the mechanical parts which communicate with the firing-chamber. Fig. 3 is a cross-sectional elevation on line *a b*, Fig. 1. Fig. 4 is a diagrammatic view showing its application to an engine of the two-cycle type, also showing the mode of wiring and means for opening and closing the electric circuit. Fig. 5 is a side view of the cam and brush, showing the brush-holder in cross-section on line *e f*, Fig. 4. Fig. 6 is a detail sectional view of the armature and connections to shaft 19 on line *c d*, Fig. 1. Fig. 7 is a detail view of the armature.

Similar numerals refer to similar parts throughout the several views.

In the construction of my igniter I provide the electromagnets 3 and 3', armature 4, shaft 19, movable electrode 12, and post 11, all installed in a plate 1, adapted to be rigidly secured to that part of an engine best adapted to communicate with the firing-chamber. The electromagnets 3 and 3' are connected in series. The terminals 14 and 14' of the magnet-coils are connected to posts 9 and 11, respectively, which are insulated from plate 1, as shown by 30 and 31. The latter post 11 projects through plate 1 and provides a fixed electrode for movable electrode 12. The former post 9 is connected to a battery 28 by the wire 27. From the battery 28 the wire 27 is extended to a brush 24, shown fastened rigidly to the engine-bearing 20 by a brush-holder 23, which is insulated from (see 32)

and provided with means of adjustment 26 on said bearing.

On shaft 21 of the engine is rigidly secured 55 a cam 22, provided with a projection 25, which communicates with brush 24 at every revolution of shaft 21. The contact of the cam with the brush completes the circuit for a two-cycle engine (in the case of a four-cycle 60 engine the cam should make one revolution to two of the crank-shaft) by means of what is termed the "ground-circuit" which is established by this connection.

The armature 4 consists of a flat piece of 65 metal projecting from a collar 15, and from said collar also projects an arm 7. Collar 15 is adapted to fit on a sleeve 16, from which is an extension 8, carrying two lugs 6 and 6', in which are inserted two set-screws 5 and 5'. 70 Said set-screws are adapted to abut against arm 7 when collar 15 is placed in position on the sleeve, and therefore form a means of adjustment for armature 4, as will be more clearly seen hereinafter.

Sleeve 16 and movable electrode 12 are rigidly connected to shaft 19, which passes through plate 1, a boss on said plate forming a bearing for said shaft. It will be seen in Fig. 6 that the sleeve 16 is slightly longer 80 than collar 15, and when placed in position on shaft 19 is held rigidly by a washer and nut 17 and 18, respectively, against a shoulder on the shaft, leaving the armature-collar free to turn and to be adjusted by the set- 85 screws. The movable electrode 12 extends to the post 11 and forms connection therewith at the point 29. Said movable electrode is held in this position by a spring 29', hooked to the armature.

An extension 2 from plate 1 serves as a support and head-plate for the electromagnets 3 and 3', which are held thereto by screw-bolts 10 and 10', and also serves as a seat for binding-post 9.

In the operation of this igniter it will be observed that cam 22 communicates with brush 24 at the proper period of ignition, closes the circuit, and excites the electromagnets, causing them to exert their magnetic force upon the armature which extends within the magnetic field. The movable electrode being normally in contact at point 29 is withdrawn by the action of the armature and its connections,

breaking the circuit and causing a spark to be emitted between the contact-points. It will be observed that when the circuit is broken by the withdrawal of the contact-points from each other the magnetic force upon the armature ceases and the contact-points are drawn to their normal position by the tension of spring 29'.

One of the many important features of this 10 igniter is that the most efficient period of ignition can be readily attained while the engine is in motion by the adjustment of the brush-holder upon bearing 20.

Having thus described my invention, what 15 I claim as new, and desire to protect by Letters Patent, is—

1. In an electric igniter for gas-engines, an armature provided with a means of adjustment, a movable electrode operatively connected with said armature, a fixed electrode projecting from a post which passes through and is insulated from a plate adapted to be secured to the cylinder of the engine, electromagnets secured to said plate electrically connected with a battery and adapted to provide energy for operating said movable electrode by means of said armature.

2. In an electric igniter for gas-engines, electromagnets attached to a plate adapted to be 25 secured to the cylinder of an engine, a wire connecting the electromagnets with a battery,

a brush stationary on and insulated from the engine, a cam adapted to communicate with the brush, a wire connecting the brush with the battery, an armature within the magnetic field of the electromagnets provided with a means of adjustment, a movable electrode operatively connected with the said armature, a fixed electrode projecting from a post which passes through, and is insulated from said 40 plate, and connected with a terminal of the electromagnet-coils.

3. In an igniter for gas-engines electromagnets connected in series and secured to a plate adapted to be attached to the cylinder of an 45 engine, an armature within the field of said electromagnets and provided with a means of adjustment, a movable electrode operatively connected with said armature, a spring to engage said armature, a fixed electrode in 50 said cylinder projecting from a post connected with said electromagnets, a battery connected with said electromagnets, a brush stationary on and insulated from the engine and connected with said battery, a cam to communicate with the brush and connected with an operative part of the engine.
